MACHINE TOOL GAUGE

Albert C. Pistorius, Dix Hills, Huntington, and Robert T. Pistorius, Lake Ronkonkoma, N.Y., assignors to Pistorius Machine Co. Inc., Hicksville, N.Y.

Filed May 3, 1971, Ser. No. 140,016

Term of patent 14 years

Int. Cl. D10—04

U.S. Cl. D52—6

FIG.1

FIG.3

FIG.2

FIG. 1 is a top plan view of a machine tool gauge showing our new design;

FIG. 2 is an enlarged fragmentary plan view, as taken from the line 2—2 of FIG. 1; and

FIG. 3 is a left end view, the right end being identical thereto.

We claim:

The ornamental design for a machine tool gauge, as shown and described.
